LIQUID SUPPLEMENT FEEDER FOR CATTLE

Lee R. Mangrum, P.O. Box 397, Giddings, Tex. 78942

Filed Sept. 29, 1972, Ser. No. 293,321

Term of patent 14 years

Int. Cl. D30—03

U.S. Cl. D30—13

FIG. 1

FIG. 2

FIG. 3

FIG. 4

FIG. 1 is a perspective view of a liquid supplement feeder for cattle showing my new design;

FIG. 2 is a top plan view;

FIG. 3 is a side elevational view; and

FIG. 4 is an end elevational view.

The vertical stripe on the end of the feeder is transparent.

I claim:

The ornamental design for a liquid supplement feeder for cattle, as shown and described.
